SMOKE PIPE CONNECTION FOR FURNACES

Filed April 15, 1927

Inventor

D. Meyer,

By *L. M. Shulow*

Attorney

UNITED STATES PATENT OFFICE.

DIRK MEYER, OF PEKIN, ILLINOIS, ASSIGNEE TO THE MEYER FURNACE COMPANY,
OF PEORIA, ILLINOIS, A CORPORATION OF ILLINOIS.

SMOKE-PIPE CONNECTION FOR FURNACES.

Application filed April 15, 1927. Serial No. 184,082.

This invention relates to a smoke-pipe connection for hot air furnaces.

The object of the invention is to provide a smoke-pipe outlet for a hot air furnace 5 that will form a thoroughly dust and smoke-tight connection between the combustion chamber or body and the casing of such furnace whereby the air space within such casing will be maintained free of such dust, or 10 smoke and other products of combustion.

Another object is to employ a one-piece smoke stub for a furnace, the same being connected to and extending from the combustion chamber or body and carried through 15 the air space between the said body and the usual surrounding casing, and through and outside the latter and providing a dust tight arrangement for preventing dust from entering the said air space.

20 In order that the invention may be fully understood the accompanying drawing is provided wherein—

Figure 1 is a plan of a furnace showing its enclosing casing in horizontal section.

25 Figure 2 is a longitudinal section, in elevation, of my smoke outlet stub arrangement, much enlarged, taken on line 2—2, Figure 1.

Figure 3 is a longitudinal section of a part 30 of the smoke outlet stub and certain flanges shown much larger than in Figure 2, and

Figure 4 is an end elevation of the outer end of the stub.

In Figure 1 is illustrated a well known 35 type of furnace with which my invention is incorporated to show its use, and wherein 1 is a drum or body wherein fuel is consumed, the character 2 designating the throat through which fuel is introduced, 3 being 40 the coal door. An auxiliary heating member or drum is indicated at 4 connected by a pipe 5 with the said drum or body 1, and a casing 6 encloses the whole structure described.

45 Though forming no part of the invention herein it may be stated that the drum or body 1 and the member or drum 4 are constructed of sheet metal parts all tightly riveted and welded together, the pipe 5 being 50 likewise riveted and welded to the named parts so that the air space within said casing 6 is maintained entirely free of any dust, smoke or gases due to the tight structure

provided. The products of combustion are carried from the body 1 into and through 55 the auxiliary drum 4 from whence they are led away to the chimney or stack, not shown.

The structure through which such products are carried is now to be described, and forms the subject of the invention. That is 60 to say, 7 is a pipe stub which may be a casting, the same opening into the said drum 4 and having at one end a flange 8 securely riveted and welded to the wall of such drum, said stub extending through the space between the said drum and the casing 6 and out through and beyond the latter as clearly shown in Figure 2. Said stub 7 has an integral flange 9 between its ends and spaced 65 at such a distance from the flange 8 as to 70 abut upon the inner side of the casing 6.

A ring 10 abuts upon the outer side of the casing and bolts 11 extending through the flange, ring and casing serve to clamp these parts firmly together, the said flange and ring preferably each having an annular cavity 12, Figure 3, to receive a cement to assist in providing a perfect seal between the stub 7, and the said casing. The extended end of 75 the said stub may receive any suitable smoke pipe connection 13 leading to the chimney or stack, not shown.

Although I have specifically referred to the drum 4 as the member to which the stub 7 is connected, as an example of the 80 place of connection, it is to be understood that said stub may be attached to any part of a furnace from which the products of combustion are conducted.

A furnace structure of such nature as to 85 insure that no dust or gases will reach the heated air space within the casing 6 is important and in keeping with this precaution dust must not be permitted to reach the air space from the outside. The provision of a 90 pipe stub such as 7, therefore, to extend from the heating drum 4 entirely through the air space and outside the otherwise tight casing and providing the clamping flange 9 and ring 10 insures that no leakage can occur 95 at this point, an exceedingly important matter where cleanliness of the rooms to be heated is to be maintained.

Not alone is a leak-tight joint provided at 100 the point named by the structure described but such structure also serves for a very 105

thorough bracing and strengthening of the casing 6, the stub in turn being braced at its outer end.

While the flange 9 is preferably integral with the stub 7 it may be otherwise carried by said stub as long as no leakage can occur between the two.

I claim—

1. The combination with a furnace including a heating drum and a casing enclosing and spaced from the same, of a pipe stub secured to and opening into said drum, extending through the space between the drum and casing and through and outside the latter and including a flange between its ends to abut against the casing at one surface thereof, and a ring abutting against the opposite side of the said casing, and means to clamp the flange, casing and ring together.
2. The combination with a furnace including a heating drum and a casing enclosing the same spaced therefrom, of a pipe stub having a flange at one end adapted to be tightly attached to said drum and including an exterior flange between its ends spaced from the first said flange a distance equal to the space between the drum and the casing and abutting upon the latter, said stub at its free end extending through and outside the casing beyond the latter, a ring or annulus adapted to slip over the free end of the stub against said casing, and means to clamp the casing between the last named flange and said ring or annulus.
3. The combination with a heating drum of a hot air furnace and an enclosing casing therefor, of a one-piece stub attached at one end to the drum and at its other end extending through and outside the casing, said stub including an integral annular flange adapted to abut upon the casing at one side, and a loose ring or annulus adapted to be clamped upon the other side of the casing,

and means extending through the flange, casing and ring or annulus securing them in 45 clamped relation.

4. The combination with the heating drum of a hot air furnace and a casing enclosing the same, of a pipe stub opening into and extending from said drum through the said 50 casing and outside and beyond the same, a flange encircling the stub between its ends closed thereto and abutting upon one side of the casing, a loose ring or annulus abutting against the opposite side of the casing, and 55 means to clamp the flange and ring or annulus upon the said casing.

5. The combination with the heating drum of a hot air furnace and a casing enclosing the same, of a pipe stub opening 60 into and extending from said drum through the said casing and outside and beyond the same, an integral flange encircling the stub between its ends and abutting against one side of the said casing, a loose ring or 65 annulus abutting against the opposite side of the casing, and means to clamp the flange and ring or annulus upon said casing, the said flange and said ring each having an annular cavity in that face thereof abutting 70 upon the casing.

6. The combination with a hot air furnace including a heating drum and a casing surrounding and enclosing the same, of a pipe stub opening into and extending from said drum and extending at its free end through and beyond the said casing, the same including an integral flange between its ends abutting upon the side of the casing facing said drum, a loose ring or annulus encircling the stub abutting upon the outer side of the casing, and means extending through the flange, casing and ring adapted to clamp those members to one another.

In testimony whereof I affix my signature.
DIRK MEYER.
